UNITED STATES PATENT OFFICE.

SALMON W. PUTNAM, 3d, OF ROCHESTER, NEW YORK, ASSIGNOR TO ARTHUR H. INGLE,
OF ROCHESTER, NEW YORK.

TOOL-MOUNTING FOR LATHES.

1,326,138.

Specification of Letters Patent. Patented Dec. 23, 1919.

Application filed October 14, 1918. Serial No. 258,012.

To all whom it may concern:

Be it known that I, SALMON W. PUTNAM, 3d, a citizen of the United States, and resident of Rochester, county of Monroe, State 5 of New York, have invented an Improvement in Tool-Mountings for Lathes, of which the following description, in connection with the accompanying drawings, is a specification, like characters on the drawings representing like parts in each of the 10 several views.

This invention relates to turret tool heads adapted for mounting a plurality of operative tools in a lathe or the like, and while 15 having other and more general fields of usefulness is well adapted and designed for mounting and clamping for selective use, different tools such as roughing and forming tools in a tire turning lathe such as 20 commonly used for initially finishing car or truck tires, and for re-finishing such tires after the treads thereof become worn in use. A principal object of the invention is to provide means whereby the several 25 tools are mounted so that they may be used selectively and any given selected tool clamped rigidly and securely for use by a simple manipulation quickly and easily effected. A further object is to provide 30 simple and compact yet reliable and conveniently operated means preferably having only a single operating lever or member adapted to move the tool turret into clamping or locking position and by a continuation 35 of the same movement to lock the turret rigidly, strongly and immovably in operative position and in a manner so as to minimize or wholly eliminate any possibility of chattering or vibration. A still 40 further object is to provide improved operating means for controlling and locking the turret preferably consisting in an adjustable toggle device that may be set so as to move into full locking position just 45 as the turret is securely clamped by a clamping member operated by such toggle. A still further object is to provide improved locking means directly engageable with the base of the turret and presenting clamping 50 faces having portions inclined in opposite directions to the direction of clamping pressure whereby the turret is centered and clamped powerfully with a wedging action that is combined with the operative effect 55 of the toggle device acting thereon. The

foregoing and other objects and advantages of the invention will more fully appear from the following detailed description, and the distinctive features of novelty will be pointed out in the appended claims. 60

Referring to the drawings:

Figure 1 is a plan view of a tool turret equipped with locking means in accordance with my invention and showing a portion of the slides of a lathe to which the same 65 may be applied;

Fig. 2 is a side view of a turret and the slides on which it is mounted with a portion of the main slide base in section;

Fig. 3 is a transverse section on line 3-3 70 of Fig. 1;

Fig. 4 is a partial plan view showing a part of the top slide with the turret holding seat and a part of the locking means for the turret, the turret itself being re- 75 moved;

Fig. 5 is a rear view of the turret and the mounting therefor, looking transversely of the lathe;

Fig. 6 is a detail elevation showing the 80 movable member co-operative with the base of the turret for locking the same;

Fig. 7 is a detail section on line 7-7 of Fig. 6; and

Fig. 8 is a rear edge view of the member 85 shown in Fig. 6.

10 indicates a portion of the relatively fixed tool base of the lathe which is located between the opposing face plates (not shown) when the device is used in a double 90 tire turning lathe, this base being equipped with a transverse dove-tailed way 11 on which is fitted for transverse adjustment a main cross slide 12, it being understood that in a double type of lathe, two of these cross 95 slides will be employed adjacent the respective base plates. On a dove-tail way 13 of this cross slide is mounted for adjustment endwise of the lathe an intermediate slide 14, the top whereof is equipped 100 with a slide way 15 to which the top slide 16 bearing the turret of the present invention, is mounted for adjustment transversely of the lathe and radially of the work. This adjustment of the top slide 16 105 on the way 15 is accomplished as shown by a screw 17 swiveled at 18 in a depending apron flange 16^a at the front of the top slide, this screw taking into a stationary nut (not shown) in the intermediate slide 14. The 110

screw 17 has keyed or otherwise fixed to its outer end a spur gear 19 which is in driven engagement with a pinion 20 fitted on a stub shaft in the apron front of the 5 top slide and having rigid therewith a squared head 20^a engageable by a wrench or like tool to turn the same. In accordance with my invention a raised boss 21 generally circular in outline is formed on the top of 10 the inner portion of the top slide 16, the top of this boss except where the same is cut away presenting a plane smooth surface on which the base of the turret is adapted to rest and swivel. This turret seat boss is 15 centrally recessed as indicated at 22 to provide a socket or seat into which an undercut base projection 23 of the turret projects, this recess being extended through the outer side of the boss 21 to permit the seating of a 20 clamp slide 24. The base of the recess 22 and its outward extension is likewise plane and has fitted and resting thereon the undercut turret base 23 and the clamp slide 24 respectively. In accordance with my in- 25 vention the turret base 23 is of somewhat smaller diameter than the body of the turret 25 from which it depends and it is formed with polygonal undercut faces, preferably and as shown eight in number. The socket 30 recess 22 in the boss 21 is formed with undercut polygonal walls that generally approximate the contour of the turret base 23 and two outer side faces 26, 27 of these undercut walls which thus present opposite 35 inclined clamping faces engaging correspondingly shaped opposite sides of the turret base, are accurately machined and finished so as to closely fit the correspondingly machined surfaces of the turret base which 40 fit thereagainst as the turret is pressed into locking position by the clamp slide 24. The intermediate walls 28, 29 of the socket recess are preferably not utilized as clamping surfaces but are rabbeted and cut away so as 45 to be clear of engagement with the turret base. The clamp slide 24 is formed with undercut machined faces 30, 31 inclined so as to fit closely and clamp coöperative machined undercut adjacent faces of the turret 50 base 23, the central portion of the slide edge between the clamping faces 30, 31 being preferably cut away as indicated at 32 so as to delimit the clamping faces and facilitate the machining thereof. The clamp slide 24 55 has its sides beveled to engage undercut ways 33 in the top of the slide 16 and leading out from the socket recess 22 and a suitable adjusting gib 34 may be provided to take up wear and insure the close sliding 60 fit of the clamp slide. The clamp slide 24 is provided at its rear end with spaced apart pivot lugs 35 in which is engaged a pivot pin 36 connected with one end of a turn- 65 buckle rod 37 the other end of which is pivoted at 38 to a short lever arm 39 pivoted at its other end at 40 to lugs 41 on the outer end of the slide 16, the turnbuckle rod 37 and the arm 39 together constituting a toggle 70 adapted when straightened to force the clamp slide 24 inward into clamping engagement with the turret base, and the turnbuckle 37 permitting a requisite range of close and accurate adjustment so that such toggle will be straightened, *i. e.*, in self-locking position 75 just as the slide 24 is strongly pressed against the turret base and with the mating faces of the turret base strongly clamped against the undercut machined faces 26, 27 of the slide boss 21. For operating this toggle lock the arm 39 has rigid, and as 80 shown integral therewith, an upstanding lever 42 which as shown in Fig. 2 preferably extends normally diagonally inward so that on moving the same upward and forward the toggle is broken and the turret released. 85 The turret 25 has vertically fitted therethrough a pivot pin 43 the lower end 43^a of which projects some little below the turret base 23 and into a somewhat elongated slot 44 in a slide bar 45 fitted to move with the clamp slide 24 in a way 46 provided therefor in the bottom of the socket recess 22. The slide bar 45 is connected to move with the clamp slide 24 by suitable means shown as a dog pointed screw 47 fitted down through the slide 24 and with its point seated in a recess therefor in the bar 45. The length of the slot 44 is such that as the toggle 37—39 is broken, the clamp slide 24 90 will first be retracted sufficiently so that its faces 30—31 will clear the sides of the turret base sufficiently to permit turning thereof, while on a further opening of the toggle the pivot pin end 43^a coming against the outer end of the slot 44 will cause the bar 45 to 95 pick up the turret and move it outward so that its inner faces will clear the undercut clamping walls 26, 27 sufficiently to permit turning of the turret as the toggle is fully opened. The turret 25 is shown as equipped 100 with two double ended roughing tools 48, 49 respectively seated in parallel sockets 50, 51 respectively provided therefor at opposite sides of the pivot 43, these tools being suitably clamped by set screws 52. Intermediate these roughing tools and at opposite sides of the turret I mount forming tools 53, 54 presenting an operative edge contour 105 adapted to finish the tire tread after the requisite amount of metal has been removed by a 110 roughing tool 48 or 49, it being understood that in common practice the roughing tool is employed with a feed in the direction of the arrow α to take off enough metal across the width of the tire so as to eliminate the 115 distorted contour T' due to wear so that by the action of the forming tool the normal contour T of the finished tire tread may be restored. For limiting the outward or opening 120 movement of the clamp slide 24 after it 125 130

has moved the turret sufficiently to permit turning thereof, a stop pin 55 may be provided set into the slide 16 in position to be engaged by the clamp slide 24. By the described mechanism the turret is powerfully and accurately located and is powerfully and securely locked in position to hold either of the roughing tools or either of the forming tools in operative position and the control thereof for moving the turret to locking position and then locking it, as well as for moving it away from locking position to release it for turning, are all accomplished by the single lever arm 42, the provision of the toggle device as described making the turret clamping mechanism self-locking as it reaches clamping position and the turnbuckle device permitting the degree of clamping pressure exerted in this locking position to be set as desired as with provision for the taking up of looseness due to wear or otherwise. The handle 42 sloping inward when in turret clamping position contributes to the holding of the toggle device locked and against casual displacement thereof. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. Apparatus of the kind described, comprising a tool turret mounted for angular adjustment to a plurality of operative positions, a seat to which said turret is fitted, and means for clamping said turret to said seat having a lost motion connection to the turret whereby it first moves to release the turret for moving with respect thereto and then moves the turret to release it for turning with respect to said seat or vice versa.

2. Apparatus of the kind described, comprising a turret mounted for angular adjustment to present any one of a series of operating tools, a mounting for said turret, said turret and said mounting having the one a polygonal base and the other a polygonal walled socket seat to receive said base, and means associated with said seat and operative transversely against said base for clamping said base to said seat.

3. Apparatus of the kind described, comprising a turret mounted for angular adjustment to present any one of a series of operating tools, a mounting for said turret, said turret and said mounting having the

one a polygonal base and the other a polygonal walled socket seat to receive said base, and means for clamping said base to said seat, said means consisting in a clamp slide formed to engage one or more of the sides of said polygonal base.

4. Apparatus of the kind described, comprising a turret mounted for angular adjustment to a plurality of operative positions and also for limited bodily lateral movement, a seat to which said turret is fitted, said turret and seat having co-operative provision whereby the turret may be clamped against angular displacement in operative position, and clamping means to lock said turret in adjusted position having means associated therewith for moving the turret bodily into and out of locking position.

5. Apparatus of the kind described, comprising a tool turret having an undercut polygonal base, a mounting therefor having a socket seat with undercut walls finished to engage one or more of the sides of said turret base, and a clamp slide having an undercut edge formed to engage said turret base and having a lost motion connection thereto for the purpose stated.

6. In combination, a tool turret having a polygonal undercut base, a mounting therefor having a socket seat with undercut walls to which said base may be clamped, a clamp slide to engage said base, and toggle operating means for said clamp slide arranged to move said slide to full locking position as said toggle is straightened.

7. In combination, a tool turret having a polygonal undercut base, a mounting therefor having a socket seat with undercut walls to which said base may be clamped, a clamp slide to engage said base, and toggle operating means for said clamp slide arranged to move said slide to full locking position as said toggle is straightened, said toggle having incorporated therewith a turnbuckle element permitting adjustment thereof for the purpose stated.

8. In combination, a tool turret having an undercut polygonal base, a slide mounting therefor having a socket seat in which said base is fitted equipped with inclined undercut walls adapted to mate with walls of said base, a clamp slide adapted to engage other undercut walls of said base and having a lost motion connection to the turret, and operating means for said clamping slide consisting in a toggle equipped with an adjustable turnbuckle element.

In testimony whereof I have signed my name to this specification.

SALMON W. PUTNAM, 3d.
